(57) **CLAIM**

The ornamental design for a quick connect coupling housing, as shown and described.

DESCRIPTION

FIG. 1 is a perspective view of a first embodiment of a quick connect coupling housing of the new design;

FIG. 2 is a front elevational view of the quick connect coupling housing of FIG. 1, the rear elevational view being a mirror image thereof;

FIG. 3 is a left side elevational view of the quick connect coupling housing of FIG. 1;

FIG. 4 is a right side elevational view of the quick connect coupling housing of FIG. 1;

FIG. 5 is a top plan view of the quick connect coupling housing of FIG. 1;

FIG. 6 is a perspective view of a second embodiment of a quick connect coupling housing of the new design;

FIG. 7 is a front elevational view of the quick connect coupling housing of FIG. 6, the rear elevational view being a mirror image thereof;

FIG. 8 is a left side elevational view of the quick connect coupling housing of FIG. 6;

FIG. 9 is a right side elevational view of the quick connect coupling housing of FIG. 6;

FIG. 10 is a top plan view of the quick connect coupling housing of FIG. 6;

FIG. 11 is a perspective view of a third embodiment of a quick connect coupling housing of the new design;

FIG. 12 is a front elevational view of the quick connect coupling housing of FIG. 11, the rear elevational view being a mirror image thereof;

FIG. 13 is a left side elevational view of the quick connect coupling housing of FIG. 11;

FIG. 14 is a right side elevational view of the quick connect coupling housing of FIG. 11; and,

FIG. 15 is a top plan view of the quick connect coupling housing of FIG. 11.

The broken lines in the drawings illustrate portions of the quick connect coupling housing and form no part of the claimed design.
